DASHBOARD FOR AN AUTOMOBILE

Karl Wilfert, Stuttgart-Degerloch, Germany, assignor to
Daimler-Benz Aktiengesellschaft, Stuttgart-Unterturk-
heim, Germany

Application May 4, 1956, Serial No. 41,352

Claims priority, application Germany November 21, 1955

Term of patent 14 years

(Cl. D14—6)

Figure 1 is a perspective view of a dashboard for an automobile, embodying my new design,

Figure 2 is a cross-sectional view taken along line 2-2 of Figure 1 and showing the cross-sectional configuration in that plane of the dashboard, for an automobile, embodying my new design,

Figure 3 is a cross-sectional view taken along line 3-3 of Figure 1 and showing the cross-sectional configuration in that plane of the dashboard, for an automobile, embodying my new design, and

Figure 4 is a cross-sectional view taken along line 4-4 of Figure 1 and showing the cross-sectional configuration in that plane of the dashboard, for an automobile, embodying my new design.

The portions shown in broken lines in Figures 1, 3 and 4 are for purposes of illustration only.

I claim:

The ornamental design for a dashboard for an automobile, substantially as shown and described.
